HYDROCARBON CONVERSION WITH THE HYDROGENATION OF THE CRACKED PRODUCTS

Reagan T. Wilson, Bartlesville, Okla., assignor to Phillips Petroleum Company, a corporation of Delaware
Filed Nov. 24, 1958, Ser. No. 775,996
5 Claims. (Cl. 208—67)

This invention relates to conversion of hydrocarbons, for example, mineral oils. In one of its aspects, the invention relates to the conversion of a residual oil having a high sulfur content and containing metal contaminants, which ordinarily are undesirable on the conversion catalyst, under conditions so as to cause the formation of sufficient hydrogen to in a unitary, highly economical, operation reform, desulfurize, hydrogenate and otherwise improve the liquid conversion products obtained during said conversion. In another of its aspects, the invention relates to a process for cracking a high sulfur residuum to produce a desirable sulfur- and olefin-free product which comprises cracking in a so-called fluid catalytic cracking operation, in the presence of a cracking catalyst, a high sulfur residuum under conditions to convert at least 50 percent thereof per pass to distillate liquid, carbon and hydrogen in an amount sufficient to remove sulfur and olefins from said liquid in a hydrogenation step, recovering hydrogen and said liquid from the cracking effluent and passing said liquid and hydrogen to a hydrogenation zone under hydrogenation conditions, maintaining said liquid and said hydrogen in said hydrogenation zone under said hydrogenation conditions until a desired sulfur and olefin removal has been accomplished and then recovering the so-treated liquid from said zone. In a further aspect, the invention relates to the conversion or upgrading of a heavy residuum in the presence of a catalyst having an unusually high metals contamination, say, in the range 2,000–25,000 p.p.m. to produce liquid products and hydrogen containing gases which suffice to desulfurize at least the 400–1,025° F. boiling range fraction of said liquid products to yield refined liquid product having a low sulfur content, of the order of about 0.7 weight percent.

The predominant use of off-gas in a typical refinery is either as a fuel or as a source of H₂ for hydrotreating processes. In many present-day processes, the hydrogen produced in catalytic reforming operations is used to hydrotreat reformer feed stocks. In most instances, the reformer hydrogen will supply most feed stock pretreatment needs. However, there are instances in which the hydrogen requirements are not met by reforming alone. For example, the calculated hydrogen production as a result of reforming the 200–400° F. fraction containing 39% naphthenes from a Middle East crude is 940 cubic feet per barrel of crude charge. Experimentally from the same stock only 720 cubic feet of H₂ per barrel were produced. Catalytic reforming of the 200–400° F. should, as calculated, produce 113,500 cubic feet of hydrogen. However, only 87,000 cubic feet actually are produced. This amount of hydrogen is not enough to desulfurize the 400–1,025° F. fraction containing 2.40 weight percent sulfur or 7.48 lb. sulfur per barrel of distillate. These figures are tabulated below.

Wafer crude	Weight percent	Vol. percent	API	Weight percent sulfur	Lbs./gal.
C ₄ and lighter	1.35	2.17			
C ₅ –200° F.	2.51	3.47	84.3		
200–400° F.	10.24	12.06	53.0	0.98	6.385
400–1,025° F.	48.70	49.30	27.4	2.40	7.415
1,025° F. +	37.20	33.00	6.3	4.91	7.583

Hydrogen production—Reforming 200–400° F. fraction based on 1,000 barrels of crude charged per day.

Hydrogen produced:

5 940 cubic feet/barrel—calculated
720 cubic feet/barrel—actual
113,500 cubic feet/day—calculated
87,000 cubic feet/day—actual

10 Hydrogen required for removal of S from 400–1,025° F. fraction:

147,900 cubic feet/day for complete removal
123,000 cubic feet/day required for 83% S removal

15 Thus, it is seen that, using the above charge stock, even reforming does not produce enough hydrogen to desulfurize the 400–1,025° F. fraction. Therefore, another source of hydrogen is needed. Such an additional source of hydrogen could be manufactured hydrogen. The cost of manufactured H₂ is from 150 to 200 dollars per million standard cubic feet.

20 It is an object of this invention to provide a process for the conversion of hydrocarbons. It is another object of this invention to convert a high sulfur residual oil in the presence of a catalyst in a manner to provide in a unitary operation for the refining of liquid products obtained during said conversion. It is another object of this invention to so operate a catalytic cracking conversion as to produce during said conversion gases and liquid products, the gases being of character and amount sufficient to refine said liquid products. It is a further object of this invention to provide a unitary hydrocarbon conversion process for the upgrading of heavy high sulfur content 25 residual oils, such as heavy Wafra residuum.

30 The residuum to which this operation is particularly adapted has the following characteristics:

IBP	F. +	1,025
API		6.3
40 Weight percent:		
S		4.9
C		83.8
H ₂		10.2
N ₂		0.39
O ₂		0.71
Mol weight		890
Softening point		108
Penetration at 77° F.		139
50 SFS viscosity at 210° F.		952
Metals:		
NiO	p.p.m.	43.7
V ₂ O ₅	p.p.m.	182.0

55 I have now found that by converting a residual oil, as herein set forth and characterized, under conditions to obtain at least 50 percent and preferably of the order of 55 or 60 percent conversion, I can produce liquid product and hydrogen containing gases in an amount sufficient to 60 hydrotreat the liquid product to produce a highly desirable final liquid product without having recourse to external hydrogen.

65 Thus, according to the present invention, there is produced a desulfurized, stable distillate by subjecting a high boiling, high sulfur residuum, to fluid catalytic cracking to form a hydrogen-rich gas, residuum-free liquid and carbon and then hydrotreating the liquid product thus obtained with hydrogen-rich gas to remove the sulfur and olefins. Still further, according to the invention, the catalyst which is used is one containing a fairly high quantity of metal 70 contaminants which are laid down on the catalyst by the

oil being converted and such a catalyst can have the following compositions, among others:

Sulfur resistant halloysite	percent	40
Filtrol 58	do	60
NiO	p.p.m.	1,160
V ₂ O ₅	p.p.m.	1,230
Iron oxide	p.p.m.	86

supported on silica-alumina having a composition of 13 percent alumina and 87 percent silica.

Area: 96 square meters per gram, and—

Filtrol 58 (montmorillonite clay)	percent	100
Alumina	do	13
Silica	do	87
Metals V ₂ O ₅ and NiO	p.p.m.	3,300

It has been found in fluid catalytic cracking tests with 1,025° F. + Wafra residuum (5 percent sulfur) over a 40-60 percent conversion range that sufficient hydrogen can be yielded at 60 percent conversion to satisfy the hydrogen requirement for hydrotreatment of total liquid effluent while at 40 percent conversion sufficient hydrogen is yielded to satisfy hydrogen requirement for hydrotreatment of the 400° F. + cycle oil. Thus, according to the invention, the catalytic cracking severity can be adjusted so that the catalytic cracking hydrogen yield and hydrotreating hydrogen requirement are in balance, resulting in an optimum yield of low sulfur distillate without use of outside hydrogen.

The following data are pertinent to show hydrogen requirement for sulfur removal as against hydrogen yield at various extents of conversion.

[Fluid catalytic cracking of 1,025° F. plus Wafra res.]

Conversion of 400° F. +, vol. percent.	59.9	52.0	46.3	40.4
Yield of feed:				
H ₂ , cu. ft./bbl.	343	208	187	133
C ₁ -C ₄ , weight percent	12.0	9.7	9.1	7.3
C ₅ -400° F., vol. percent	31.7	37.4	24.9	23.0
400° F. +, vol. percent	40.1	48.0	53.7	59.6
Catalyst deposits, weight percent	23.3	22.1	19.6	18.3
Sulfur, lb./bbl.	0.47	0.45	0.46	0.44
C ₅ -400° F.	5.72	6.31	7.00	8.51
400° F. +				

[Hydrogen requirement for complete sulfur removal,² cu. ft./bbl.]

C ₅ -400° F.	19	18	18	18
400° F. +	229	252	280	340
Total	248	270	298	358

¹ To catalyst deposits and materials boiling below 400° F.

² Assume 40 cu. ft. hydrogen consumed/lb. sulfur removed.

It has been found and this is a particularly very advantageous feature of the present invention that, as the degree of conversion is increased, the hydrogen make is increased as well as finding a decrease in sulfur present in the 400° F. + fraction. This is shown in the foregoing table in which at 40.4 percent conversion the pounds per barrel of sulfur are 8.51 while at 59.9 percent conversion this figure is reduced to 5.72, the hydrogen make having increased from 133 at 40.4 percent conversion to 343 cubic feet per barrel, respectively.

Thus, the invention provides an operation in which a Middle East crude residuum which ordinarily is extremely difficult to treat advantageously is treated, as claimed. This treatment results in various advantages, some of which are evident upon a study of this disclosure, the drawing and the appended claims.

Referring now to the drawing, there is shown diagrammatically an operation according to the present invention. The drawing is now described in connection with a specific operational example.

Example

318,700 pounds per day of 1,025° F. + residuum from Wafra crude having an API gravity of 6.3 is charged via

line 1 to a catalytic residuum cracker 2. Cracker 2 is operated in known fluid catalytic process manner and at 10 pounds p.s.i.g., 892° F., a space velocity of 1.18 and a residence time of 10 minutes. The catalyst is a silica-alumina cracking catalyst containing 87 percent silica and 13 percent alumina. Mean weight of carbon on the catalyst is about 2.38 weight percent. Fifty pounds of steam per barrel of feed are charged to the unit. Conversion obtained is 60 percent. 245,400 pounds per stream day are yielded from the cat cracking operation and are passed via line 3 to fractionator 4 wherein C₄ and lighter materials and H₂S pass overhead through line 5 into fractionator 33. Fractionator 33 operates as a deethanizer with ethane and lighter together with H₂S passing overhead through line 11 and C₃ and C₄ materials passing out as a bottom fraction through line 10. A C₅ and heavier fraction is removed from fractionator 4 and passed to fractionator 7 via line 6 and in the amount of 194,407 barrels per stream day. Fractionator 7 operates to remove overhead, through line 8, 73,938 barrels per stream day of material boiling in the C₅-400° F. range and 120,469 barrels per stream day of 400° F. + is removed via line 9. 21,897 pounds per stream day of C₂ and lighter and H₂S are passed through line 11 to compressor 12 wherein they are compressed to 600 p.s.i.g. and are thence passed by line 13 to a H₂S removal unit 14 wherein 9,911 pounds of H₂S are removed overhead via line 34. C₂ and lighter material which has had H₂S removed is passed via line 31 and line 32 to hydrotreaters 15 and 16. The net gas

make resulting from the operation of the residuum cracker 2 is 730 cubic feet per barrel of feed charged, having a composition of 56 mol percent hydrogen, 26 mol percent methane and 18 mol percent ethane. 73,938 pounds per stream day of C₅-400° F. is charged to hydrotreater 15. This stream contains .565 weight percent sulfur, has a bromine number of 106, a refractive index of 1.4242 at 20° C., a research octane number of 93.8 with 3 ml. of TEL and an API gravity of 57.1. Hydrotreater 15 is operated to produce a gasoline having a sulfur content of 0.1 weight percent or less. Conditions in the hydrotreater 15 are 600 p.s.i.g., 650° F., a liquid hourly space velocity of 5 and a hydrogen charge of 2,000 cubic feet per barrel of hydrotreater feed with a net hydrogen consumption of 87 cubic feet per barrel of residuum cracker feed required to remove sulfur and olefins to the desired degree. The effluent from hydrotreater 15 is removed to high pressure liquid gas separator 18 which is operated at 500 pounds pressure and wherein ethane and lighter are passed via line 35 to recycle compressor 36 and thence to line 13 and H₂S removal unit 14. The liquid phase from the liquid gas separator 18 passes through line 21 and pressure reduction valve 22 through which pressure is reduced to 10 p.s.i.g. and enters an atmospheric pressure liquid gas separator 26 where a further separation is made of light gaseous material and product naphtha. The gas removed by this pressure reduction operation is recycled via line 30 to line 5. Product naphtha contains 0.095 wt. percent S and is removed via line 27 in the amount of 73,938 pounds per stream day. Returning to fractionator 7, 120,469 barrels per stream day of material boiling above 400° F. are passed via line 9 into hydrotreater 16. This material has a sulfur content of 4.2 weight percent, a pour point of +15° F., an aniline point of 78.6, an API gravity of 14.3 and a BMC¹ of 83.39. Ethane and lighter material enter hydrotreater 16 via line 32 and line 9 and this hydrotreater is operated to reduce the sulfur content to 0.75 weight percent or less. The hydrogen

required to removed sulfur and olefins to the desired extent is 207 cubic feet per barrel of feed. The operating conditions of hydrotreater 16 are 750° F., 600 p.s.i.g., a liquid hourly space velocity of 1 and a gas circulation rate of 2,000 cubic feet per barrel. The 400° F. + material is removed from the hydrotreater 16 via line 17 to a

high pressure liquid gas separator 19 operated at 500 pounds per square inch wherein gaseous material is removed via line 20 to line 35 and recycle compressor 36. The net gas product as a result of the operation of the cat cracker is 730,000 cubic feet per stream day of which 320,880 is H₂ of which 294,000 is consumed. The recycle rate is maintained at 1,500,000 cubic feet per day. Product distillate is removed from high pressure separator 19 via line 23 and passes through a pressure reduction valve 24 through which pressure is reduced to 10 pounds per square inch and thence into a low pressure separator 25 wherein a separation is made between product distillate and the light gaseous material. Product distillate in the amount of 120,469 pounds per stream day containing .714 weight percent S is removed via line 28 and the gaseous material is removed overhead via line 29 and passes to line 30 and is recycled via line 30 to fractionator 33 via line 5.

It will be noted by one skilled in the art in possession of this disclosure that whereas ordinarily process conditions are adjusted to make a maximum amount of product distillate with a minimum amount of gas, the present invention departs from this practice to accomplish its advantageous results.

A particularly important and advantageous feature of the process of this invention is that the fuel gas produced from the process, though it is produced in a somewhat lesser amount, has a higher B.t.u. content than that obtained from the conversion operation. The following table gives the principal constituents of the original gas composition and the gas composition after the hydro-treating operation.

	Mol percent	B.t.u./cu. ft.
Original gas composition:		
H ₂	56	
CH ₄	26	669
C ₃ H ₈	18	
Gas composition after hydrotreating:		
CH ₄	54	
C ₂ H ₆	37	1,093
H ₂	9	

While it has been disclosed herein that the catalyst contamination can be in the range of about 2,000 parts per million to as high as 25,000 parts per million or higher, the presently preferred range is 3,300-6,000 parts per million. While the catalyst, per se, does not form a part of the invention, the use of such a highly contaminated catalyst is one of the unique features of the claimed process in the now preferred form thereof.

In the following tabulation are shown conditions and ranges of conditions applicable in this invention in the various aspects thereof. It will be understood by one skilled in the art that the invention is limited only as expressed in the claims appended hereto.

CATALYTIC CRACKING

	Specific	Range
Temperature	892° F.	800-1,000° F.

Catalysts which can be used for hydrotreating in this invention are those which are known in the art which are capable of catalyzing this step and include cobalt molybdate, molybdena-alumina, and tungsten and nickel sulfides. A catalyst which is considered particularly applicable is that described in Serial Number 668,926, filed July 1, 1957, now Patent No. 2,953,515, by William C. Lanning. This catalyst comprises the oxides of vanadium, 15 cobalt and molybdena deposited on porous active alumina. 20

From the foregoing, it is evident that the invention in its several aspects provides the art with a modus operandi and process whereby in a highly economical and efficient manner a very difficultly treatable heavy residuum material, such as Wafra 1,025° F.+residuum, can be advantageously processed to form desirable products without recourse to external hydrogen and, therefore, even at a place where external hydrogen is not readily available.

The charging stock to which this invention is particularly applicable has been indicated to be a heavy residuum. However, the invention is applicable to topped crudes or residua from any type of crude. However, in terms of API gravity, a crude fraction having a gravity ranging from 5 or less to 30 API can be used and the extent 30 of conversion will depend upon the feed stock. Thus, when charging a stock having a fairly low sulfur content, the distillate produced will contain a quantity of sulfur such that at the lower extent conversion, sufficient hydrogen will be produced for hydrotreating purposes. Thus, 35 when less hydrogen is required to accomplish the desired hydrotreatment, a conversion level which is lower than that required in the case of a higher sulfur content will be employed.

Reasonable variation and modification are possible 40 within the scope of the foregoing disclosure, drawing and the appended claims to the invention, the essence of which is that a high sulfur containing heavy oil is cracked to an extent of conversion such that there is obtained a gas containing hydrogen sufficient to hydrotreat the liquid 45 products obtained from said conversion or at least a portion thereof to obtain a distillate material having a low sulfur content and a low olefin content, if any, in the now best mode of operation employing a cracking catalyst 50 which has purposefully been allowed to become highly 55 contaminated with metal contaminants.

I claim:

1. A process for cracking a high sulfur residuum to produce a desirable sulfur- and olefin-free product which comprises cracking said residuum in a fluid catalytic cracking operation, in the presence of a cracking catalyst having a quantity of metal contaminant, at a temperature in the range of about 800-1000° F., and at a pressure not in excess of 150 p.s.i.g., to convert at least 30 percent thereof per pass to produce a distillate liquid and hydrogen 60 in an amount sufficient to remove sulfur and olefins from said liquid in a hydrogenation step, recovering said liquid from the cracking effluent, separating said liquid into a first stream of C₅ to 400° F. fraction and a second stream of 65 400° F. plus fraction, passing said first stream to a 70 first hydrogenation zone, passing said second stream to a second hydrogenation zone, recovering hydrogen from said cracking effluent and passing a portion of the hydrogen thus recovered to said first hydrogenation zone, operating said first hydrogenation zone under first reaction 75 conditions so as to effect the desired sulfur and olefin re-

removal, passing a second portion of the recovered hydrogen to said second hydrogenation zone, operating said second hydrogenation zone under second reaction conditions so as to effect the desired sulfur and olefin removal; said first reaction conditions comprising a temperature in the range of about 500-800° F., a pressure in the range of about 150-1500 p.s.i.g., and a liquid hourly space velocity in the range of about 1 to 25; said second reaction condition comprising a temperature on the order of at least about 100° F. higher than the temperature of said first reaction condition, a pressure in the range of about 150-1500 p.s.i.g., and a liquid hourly space velocity in the range of about 1 to 25.

2. A process according to claim 1 wherein the conversion per pass is in the range of 30-60 percent and 15 wherein the extent of conversion is made dependent upon the sulfur content of the charging stock used in the process.

3. A process for cracking a high sulfur crude to produce a desirable sulfur- and olefin-free product which comprises cracking in a fluid catalytic cracking operation, in the presence of a cracking catalyst having a quantity of metal contaminant, at a temperature in the range of about 800-1000° F., at a pressure not in excess of about 150 p.s.i.g., and at a liquid hourly space velocity in the range of about 0.3 to 5 feet per second, a high sulfur 25 residuum obtained from said crude to convert at least 30 percent thereof per pass to produce a distillate liquid, and to produce hydrogen in an amount sufficient to remove sulfur and olefins from said liquid in a subsequent 30 hydrogenation step, recovering said liquid from the cracking effluent and passing said liquid to a hydrogenation zone, recovering hydrogen from said cracking effluent and passing the hydrogen thus recovered to said hydrogenation zone, the hydrogen thus recovered being substantially the 35 only source of hydrogen for said hydrogenation zone, operating said hydrogenation zone at a pressure in the range of about 150 to about 1500 p.s.i.g., at a temperature in the range of about 500 to about 800° F., and a liquid hourly space velocity in the range of about 1 to about 25; until a desired sulfur and olefin removal has 40 been accomplished, and recovering the thus treated liquid from said hydrogenation zone.

4. A process for cracking a high sulfur crude to produce a desirable sulfur- and olefin-free product which comprises cracking in a fluid catalytic cracking operation, in the presence of a cracking catalyst having a quantity of metal contaminant, at a temperature in the range of about 800-1000° F., at a pressure not in excess of about 150 p.s.i.g., and at a liquid hourly space velocity in the range of about 0.3 to 5 feet per second, a high sulfur 45 residuum obtained from said crude to convert at least 30 percent thereof per pass to produce a distillate liquid, and to produce hydrogen in an amount sufficient to remove sulfur and olefins from said liquid in a subsequent hydrogenation step, recovering said liquid from the cracking effluent and passing said liquid to a hydrogenation

zone, recovering hydrogen from said cracking effluent and passing the hydrogen thus recovered to said hydrogenation zone, the hydrogen thus recovered being substantially the only source of hydrogen for said hydrogenation zone, operating said hydrogenation zone at a pressure in the range of about 500 to about 750 p.s.i.g., at a temperature in the range of about 650 to about 750° F., and a liquid hourly space velocity in the range of about 1 to about 5; until a desired sulfur and olefin removal has been accomplished, and recovering the thus treated liquid from said hydrogenation zone.

5. A process for cracking a 1025° F. plus residuum from Wafra crude to produce a desirable sulfur- and olefin-free product which comprises cracking in a fluid catalytic cracking operation, in the presence of a silica-alumina cracking catalyst, at a temperature in the range of about 800-1000° F., at a pressure of approximately 10 p.s.i.g., at a liquid hourly space velocity in the range of about 0.3-5 ft./sec., and a residence time of approximately ten minutes, a 1025° F. plus residuum from Wafra crude to convert approximately 60 percent thereof per pass to produce a distillate liquid and hydrogen in an amount sufficient to remove sulfur and olefins from said liquid in a hydrogenation step, recovering said liquid from the cracking effluent, separating said liquid into a first stream of C₅ to 400° F. fraction and a second stream of 400° F. plus fraction, passing said first stream to a first hydrogenation zone, passing said second stream to a second hydrogenation zone, recovering hydrogen from said cracking effluent and passing a portion of the hydrogen thus recovered to said first hydrogenation zone, operating said first hydrogenation zone at a pressure of approximately 600 p.s.i.g., at a temperature of approximately 650° F., and at a liquid hourly space velocity of approximately 5 to produce a product having a sulfur content of approximately 0.1 weight percent or less, passing a second portion of the recovered hydrogen to said second hydrogenation zone, operating said second hydrogenation zone at a pressure of approximately 600 p.s.i.g., at a temperature of approximately 750° F., and at a liquid hourly space velocity of approximately 1 to produce a product having a sulfur content of approximately 0.75 weight percent or less.
